UNITED STATES PATENT OFFICE

2,611,317

ROTATING NOZZLE FOR ROCKETS

Alfred Africano, Weehawken, N. J., assignor to
the United States of America as represented
by the Secretary of War

Application March 8, 1946, Serial No. 652,868

3 Claims. (Cl. 102—50)

1

The invention relates to improvement in rocket projectiles and more particularly to an improved rocket projectile having a rotating nozzle for aligning the thrust and to stabilize the launching and flight thereof.

Efforts have been made to bring about rotation of rocket projectiles during launching in order to stabilize flight. Since such projectiles are relatively heavy, the energy required to produce the necessary rotation may be excessive, and where the entire projectile is rotated in launching it has a tendency to drift away from the axis of the launching tube. High speed turbine rotors have been mounted in the tail assembly of projectiles to provide a gyroscopic effect and thus stabilize the flight, but such rotors are difficult to manufacture and mount for rotation, and add to the weight of the projectile. Further, rotation of the entire projectile and motor tends to interfere with the satisfactory trapping and burning of the propellant charge within the rocket motor.

All of these difficulties may be avoided by the use of a rotational nozzle connected to the rocket projectile in such manner that only the nozzle will be rotated at high speed and any rotation of the projectile itself would be quite slow.

An important object of my invention is to provide a rotating nozzle for rocket projectiles which will align the effective thrust of the projectile, and which will tend to counteract the tendency of the projectile to drift away from the axis of the launching tube.

Another object of my invention is to provide a rocket projectile in which only the nozzle would be rotated at high speed, thus stabilizing the rocket in flight.

It is a further object of the invention to provide an improved rocket nozzle construction which may be manufactured easily and which may be readily tested in static tests.

Other objects and advantages of the invention will be apparent during the course of the following description, and in the accompanying drawings, forming part of the specification, in which like numerals are employed to designate like parts throughout the same.

In the drawings:

Figure 1 is an elevation of a rocket projectile, partly in section, embodying the invention and shown within a section of a launching tube,

Figure 2 is a stern end view of rotating nozzle of the type herein described, including a transverse section of a launching tube, taken on the line 2—2 of Figure 1,

2

Figure 3 is a fragmentary section of a modification of the method of connecting the nozzle to the projectile, and

Figure 4 is a similar view of another modification of the same.

In the drawings, particularly Figure 1 in which is shown a preferred embodiment of my invention, the numeral 5 designates a portion of a rocket launching tube and the numeral 6 designates the rear portion of the body of a rocket projectile having a chamber or cavity 7 in which a motor (not shown) is housed, a throat portion 8 and a discharge opening 9 through which the combustion gases from the motor pass out of the projectile. Screw threads 10 are provided in the body of the projectile 6 and around the opening 9 to permit screw-threaded attachment of a ring 11, said ring being arranged with an annular flange or projection 12 providing raceway for the ball bearings 13.

The numeral 14 designates a funnel shaped tubular expanding cone, which with the throat portion 8 and the discharge opening 9, constitute the nozzle of the rocket projectile, the expanding cone alone, however, being hereinafter generally referred to in this specification and in the appended claims as the "nozzle." The nozzle 14 is provided with an annular flange 15 formed integral with its body at the smaller diameter end to receive the flange 12 and form additional bearing for the ball bearing 13, and it is arranged for screw threaded engagement with a flange ring 16, thus providing means for attaching the nozzle 14 to the projectile 6. It also supplies another annular bearing surface for the ball bearings 13.

The inner surface of the nozzle 14, which is coaxial with the throat portion 8 of the projectile 6 and tapers uniformly to the end of greatest diameter, is provided with a plurality of upstanding vanes or ridges 17 disposed at an angle to the axis of the nozzle 14. A detachable ring 18 arranged about the periphery of the nozzle 14 at its largest diameter end is provided with a number of lugs 19 about its exterior circumference to provide pivoted engagement for a plurality of folding fins 20 which provide flight stability, the said fins being so shaped that when folded against the sloping exterior sides of the nozzle 14 they will fit within the launching tube 5.

In the modified method of connecting the projectile 6 to the nozzle 14, as shown in Figure 3, a ring 21 arranged for screw-threaded engagement with the screw threads 10 in the projectile 6 is provided with an annular flange 22, forming raceways for double rows of ball bearings 23.

The flange 24 on the nozzle 14 is arranged for screw-threaded connection with a collar 25. In the modification shown in Figure 4, the projectile 6 is formed with an annular flange 26 providing a raceway 27 for the ball bearings 28. An annular ring 29 is welded at 30 to the nozzle 14, the said ring 29 being spun or upset as at 31 to retain the ball bearings 28. In all other respects the nozzle 14 will be arranged as heretofore described.

In operation, the combustion gases from the rocket motor (not shown) flow rearward through the throat portion 8 and pass from the projectile 6 through the opening 9 and into the nozzle 14 where they activate the said nozzle by their action against the angularly disposed vanes 17 attached to the inner surface, causing the said nozzle to rotate at great speed and producing an effect which will tend to keep the rocket aligned in the launching tube 5. As the nozzle 14 rotates, the thrust of the combustion gases passing rearward provides an aligned thrust for launching the projectile. The revolving nozzle tends to homogenize the jet of the gases and avoid non-axial thrusts caused by a misaligned nozzle.

As the projectile leaves the launching tube 10 the rotation of the nozzle causes the fins 20 to swing radially outward on their pivots thus providing stabilizers for the rocket in flight as is well known in the art. The forward thrust of the rocket is taken up by the bearings and the projectile continues in flight without rotating, avoiding the tendency of the projectile to drift away from the desired line of flight.

A further advantage of the rotating nozzle lies in the fact that its functioning may be checked in static tests wherein the nozzle may attain the same speed of rotation during the test as it would attain in flight.

The arrangement of the fins 20 on the detachable ring 18 permits their removal from the projectile whenever the use of such fins is not desirable.

It is to be understood that the form of my invention, herewith shown and described, is to be taken as a preferred example of the same, and that various changes in the shape, size and arrangement of parts may be resorted to without departing from the spirit of my invention, or the scope of the subjoined claims.

Having thus described my invention, I claim:

1. A rocket projectile provided with a motor chamber and a discharge nozzle axially aligned with the said motor chamber, the forward portion of said discharge nozzle being formed integral with the said motor chamber and its rearward

portion being a tubular expanding cone formed separate from the said motor chamber, a ring member on said forward portion of said discharge nozzle cooperating with a second ring member on said tubular expanding cone to form a raceway for antifriction bearings and a plurality of upstanding vanes fixed along one edge to the inner surface of said cone and disposed at an angle to the axis thereof, said vanes being responsive to the outward flow of propellant gases from the motor chamber whereby the said rearward portion is revolved in flight.

15. A rocket projectile having a motor chamber and provided with a throat leading to an opening at its stern end, a rotatable conical nozzle axially aligned with the said opening and having a plurality of upstanding vanes fixed at an angle to its inner surface, said vanes being positioned so that they intercept the outward flow of gases 20 from the motor chamber, a threaded and flanged ring member cooperating with the adjacent ends of the said motor chamber and the said nozzle to form a raceway for anti-friction bearings, and a plurality of stabilizing fins foldable against the 25 exterior sides of the nozzle when the rocket is in launching position.

3. A rocket projectile having a motor chamber provided with an integral throat, a separate rearwardly directed axially aligned rotatable flared nozzle, the axis of rotation of said nozzle being coincident with the axis of said chamber, an annulus on the outward end of said throat, a flanged retainer ring member on said nozzle of greater diameter than said annulus and cooperating therewith to form a raceway for anti-friction bearings, a plurality of upstanding vanes secured along one edge to the inner surface of said nozzle and disposed at an angle to the axis thereof, a lug carrying ring embracing the periphery of said nozzle at its largest diameter and a plurality of foldable fins in pinned relation with said lugs and nesting against the exterior sides of the said nozzle when the rocket is in launching position.

ALFRED AFRICANO.
